CATAMENIAL PAD

Harrison R. Williams, Glens Falls, N. Y.

Application February 8, 1928, Serial No. 252,721

6 Claims. (CL 128—290)

This invention relates to catamenial pads or bandages and has for its object to provide a pad composed of a multiplicity of loosely felted layers of highly absorbent material, which layers have the edges thereof sealed together by interlocking of their fibers.

A further object of the invention is to provide a pad of the kind referred to in which the end portions of the pad are made thin by the application of a light pressure thereto, the portion between the ends being left uncompressed, so that the ends of the pad may fit closely against the body of the wearer and will not bulge the garments.

Other objects and advantages will hereinafter appear.

In the drawing forming part of this specification:

Figure 1 is a plan view of a pad embodying features of the present invention, a portion of the gauze wrapping being shown unfolded;

Figure 2 is an end elevation of the pad showing, in dot and dash line, the web of material from which the pad is formed;

Figure 3 is a side elevation of the pad;

Figure 4 is a fragmentary elevation, partly broken away; and

Figure 5 is an elevation showing the pad material before it has been compressed to form a sealed edge.

As shown in Fig. 5, the pad material consists of a multiplicity of thin crinkled layers or sheets 1 of loosely felted fibers such as cellulose fibers of the thinnest and most tenuous material that can be manufactured. This material is soft and highly absorbent, and a pad of the material can be readily disintegrated by water when it has served its purpose.

Pads of the prior art, constructed of this material, have been cut along the sides thereof by revolving knives operated in a manner to effect a saw cut. The material in a finished pad so made is uncompressed at the edges thereof, and the various layers of the pad are unconnected to one another.

It is desirable that the edges of the pad be sealed, since the pad desirably contains, between the layers composing it, chemicals in powdered form and the sealing of the edges serves to retain such powdered chemicals within the pad.

I have discovered that by severing the individual pad from the web of pad material by a shear cut as by blanking the individual pads from the web by means of a die and a pressure member coating therewith, the edges of all of the layers

1 of the pad may be compressed together to form a sealed edge 2 as shown in Fig. 4. Owing to the loose character of the felting of the fibers of the individual sheets, and to the fact that the individual sheets are uncalendered, the application of the cutting pressure is effective to interlock the fibers of the several layers 1 and thereby to unite the layers to form the sealed edge 2, and this without resorting to the objectionable practice of using adhesive. The cutting of the pad 10 may be effected by the direct application of pressure simultaneously around the entire edge of the pad. But preferably, in order to avoid the high pressure required for cutting by this method, and to avoid possible compacting of the body 15 of the pad material, the pad material is positioned over a die having an opening therein of the desired configuration, and a pressure roller is passed across the opening in the direction of the length of the pad so that the cutting progresses along the edges. In this way a progressive cut, rather than a direct shear cut, is effected. The sheet material is crinkled, or corrugated, the corrugation extending longitudinally of the pad so that the pressing down of the side edges of the outer layers of the pad results only in a slight flattening out of the corrugations and does not cause such layers to be put under any substantial tension. The inner films or sheets of the pad thus formed are pressed together slightly 30 adjacent the cut edges and due to their elasticity they cause the pad to bulge out slightly above and below the sealed edge. Shallow reentrant angles are thus formed along the sides of the pad with the sealed edges at the vertices thereof. 35 The sealed edge is therefore held out of contact with the body of the wearer.

The provision of the sealed edges, as described, produces several important advantages over the pads of the prior art, besides those already mentioned. In such prior pads the longitudinal edges of the plies are uncompacted and unconnected. These raw edges, which of necessity press against the body of the wearer, are as highly absorbent as any portion of the pad, and permit of rapid 40 vaporization of the vaporizable content of the deposited fluid, both because of the relatively large surface area of such edges exposed to the air, and because the edges are directly exposed to the body heat. As a consequence, the formation of a hard, irritating, caked or granular deposit in the raw edges of such pads is unavoidable. This involves serious discomfort, because of the chafing produced by such hardened raw 45 edges.

In such prior pads, the several plies of which the pads are formed extend parallel to one another throughout their widths. Due to this fact and to the further fact that no provision is made 5 for securing the plies to one another, the pads do not adapt themselves to, nor admit of, transverse distortion in use otherwise than by bending them convexly upward in their entirety and throughout their entire lengths. Such flexure or 10 bending necessarily imparts a pronounced longitudinal rigidity to the pad, which opposes the folding upward of the ends into conformity to the body. Objectionable bulging of the garments of the wearer necessarily results. Securement of 15 the pad immovably in place is also rendered awkward and difficult.

In the improved pad herein disclosed, on the other hand, the act of forming the sealed edges intermediate the top and bottom of the pad causes 20 the plies above the sealed edges to become upwardly convex and the plies below the sealed edges to become downwardly convex. As a consequence, pressure applied to the opposite side edges of the pad urging such edges toward one 25 another causes the upwardly convex plies to bulge upward and the downwardly convex plies to bulge downward, so that a separation of the plies is effected about midway of the height of the pad, except at the edge portions thereof. Objectionable 30 longitudinal stiffening of the pad is avoided, both because of the fact that about half of the material, the lower half, is bulged downward, and because the longitudinal edges are drawn together and turned inward where sealed so that 35 the edge portions are rendered pliable. The end portions, therefore, may be turned upward, as desired, to fit snugly and comfortably against the body.

As has been pointed out, a slight re-entrant 40 angle is formed at each of the sealed edges, so that the sealed edges do not come into contact with the body. There is relatively little tendency of the fluid to penetrate the sealed edges, owing to the compacting of the material at such edges. 45 The edges, moreover, do not offer a large superficial area in proportion to their volume, and do not, therefore, conduce to rapid vaporization of the vaporizable content of the fluid. The objectionable tendency to produce hardened chafing 50 areas in contact with the body at the edges of the plies is, therefore, eliminated.

The width of the web from which the pads are cut is equal to the length of a finished pad so that the ends of the pad do not require to be cut. 55 The ends are accordingly unsealed. This is not a drawback, however, for the reason that the ends are upturned in use so that there is little or no danger that powder, if present in the pad, will spill out at the ends.

It is desirable to taper the thickness of the 60 pad at the ends 3 thereof as best indicated in Fig. 3 of the drawing, so that the ends will not cause the garments of the wearer to bulge objectionably. To this end the web of material, 65 prior to the severance of the individual pads therefrom, may be passed between rollers of suitable configuration to compress the material slightly at the margins of the web so that it will be shaped in cross-section like the pad shown in 70 Fig. 3. Owing to the extreme softness and looseness of the material, a compacting of this degree does not render the ends of the pad hard or un-

comfortable to the wearer, but does reduce the dimensions at the ends. The pressing of the pads thin at the ends has the advantage that powder contained in the pad is prevented at all times from spilling out at the unsealed ends. 5

When the pad has been rolled and cut in the manner described it is enfolded in the usual gauze wrapping 4.

While I have illustrated and described in detail certain preferred forms of my invention, it is to 10 be understood that changes may be made therein and the invention embodied in other structures. I do not, therefore, desire to limit myself to the specific construction illustrated, but intend to cover my invention broadly in whatever form its 15 principle may be utilized.

I claim:

1. A catamenial pad comprising a multiplicity of sheets of loosely felted fibers, said pad being compressed at the ends thereof to form tapering 20 ends, and being uncompressed intermediate the ends.

2. An absorbent pad comprising a multiplicity of sheets of loosely felted fibers, said sheets being compressed and mechanically united along the 25 longitudinal edges to form sealed edges between the top and bottom of the pad, said sealed edges lying at the vertices of reentrant angles formed by the side surfaces of the pad, and therefore in position to be maintained out of contact with 30 the body of the wearer.

3. A catamenial pad having a body portion and a pair of tapered end portions and comprising a multiplicity of sheets of loosely felted fibres 35 extending throughout said portions, the body portion being substantially uncompressed throughout its length, and the end portions being compressed so that the extreme ends of said end portions are of substantially less thickness than the body portion, parts of the end portions being 40 compacted to interlock the fibrous components in hard, retentive formation, but the extreme ends of the end portions being compressed only to a degree insufficient to render them hard or 45 uncomfortable to the wearer.

4. A catamenial pad having a body portion and a pair of tapered end portions, and comprising a multiplicity of sheets of loosely felted fibres extending throughout said portions, the body portion being substantially uncompressed throughout 50 its length, and the end portions being compressed to a degree sufficient to make the extreme ends of said portions substantially thinner than the body portion, but insufficient to render them hard or uncomfortable to a wearer. 55

5. A catamenial pad comprising a multiplicity of sheets of loosely felted fibres, said pad being compressed at an end thereof to form a tapering end, and being uncompressed intermediate its 60 ends.

6. A catamenial pad having a body portion and a pair of end portions and comprising a multiplicity of sheets of loosely felted fibres extending throughout said portions, the body portion being substantially uncompressed throughout its length, and an end portion being tapered and compressed to a degree sufficient to make the extreme end of said portion substantially thinner than the body portion, but insufficient to render it hard or 65 uncomfortable to a wearer. 70
